UNITED STATES PATENT OFFICE

ERNEST MOONEY, OF YORK, ENGLAND

LUBRICATING DEVICE FOR RAILWAY VEHICLE AXLES

Application filed February 4, 1931, Serial No. 513,432, and in Australia April 14, 1930.

This invention relates to lubricating devices for railway vehicle axles and of the kind in which an absorbent pad connected to or formed integral with capillary feeders dipping into the oil in the axle-box is supported in contact with the journal by means of a spring frame. As at present constructed difficulty is often experienced in removing such lubricating devices from the axle-boxes when the axle is in position owing to the restricted space left between the end of the axle and the axle-box and also because the device has to be forced outwardly to enable it to pass the enlarged end or fillet of the axle. Now the chief object of the present invention is to construct the frame of an axle lubricating device of this kind so as to overcome this disadvantage.

According to the invention the pad of the lubricating device is mounted on a spring frame whose pad-supporting or cradle portion is adapted to be depressed and flattened out so as to increase its width and allow the device as a whole to be drawn past the fillet on the end of the axle.

In an embodiment of the invention the pad may be secured to the upper ends of transverse spring leaves or arms whose lower ends are fixed on a base or supporting frame. Said spring leaves or arms may be connected by a longitudinal member or members one of which may serve to give rigidity to the edge of the pad, whilst the other may be extended beyond the edge of the pad and the end of the axle so as to afford a finger plate whereby the device may be conveniently flattened when in position in an axle box. The extended ends of the longitudinal members may also be provided with rigid arms hinged or pivoted to the base or supporting frame. Sufficient slack is left in the middle part of the pad to allow free movement of the spring leaves or arms, and in this connection the pad may comprise two bearing surfaces joined together by a strip of flexible material, whilst if desired a gap may be left in the middle so as to allow the axle to be lubricated by splash.

In order that the invention may be clearly understood and readily carried into effect,

the same will now be more fully described with reference to the accompanying drawings; in which:

Figure 1 is a sectional side elevation of an axle-box and journal having a lubricating device constructed according to the invention.

Figure 2 is a sectional plan of Figure 1, the absorbent pad being broken away for the sake of clearness.

Figure 3 is a sectional end elevation of Figure 1.

Figure 4 is a similar view to Figure 3, but shows the lubricating device in the depressed and flattened position.

Referring to the drawings, 1 is the absorbent pad connected to or formed integral with capillary feeders 2 dipping into the oil (not shown) in the axle-box 3 and supported in contact with the journal 4 by means of a spring frame. The outer edges of the pad 1 are secured to the upper ends of the transverse spring leaves 5 whose lower ends are riveted or otherwise secured on a base or supporting frame made up of longitudinal members 6 and transverse members 7.

As shown there are two spring leaves 5 at each end of the pad 1 and in order to obtain the maximum resiliency these are arranged so as to extend substantially from side to side of the device by securing the opposite ends of adjacent spring leaves 5 to the opposite side members 6 of the base frame.

The free ends of the spring leaves 5 on each side of the device are connected by longitudinal members 8, 9 the upper member 8 on each side having secured thereto the edge of the pad 1, whilst the lower member 9 on each side is extended beyond the end of the pad 1 and is bent to avoid the end or fillet 4^x of the axle journal 4 so as to afford a finger plate whereby the device may be conveniently flattened for withdrawal.

The extended part of each member 9 is also provided with a rigid arm 10 each of said rigid arms being pivotally mounted on a bracket 11 on one of the transverse members 7 of the supporting frame and each arm having a slot 12 through which the pivot pin

13 passes, the object of this being to allow

100

sliding movement of the arms 10 when the spring leaves are flattened.

In use, when it is desired to remove the device from the axle-box 3, the spring leaves 5 are flattened by pressing on the finger plates afforded by the members 9, thus bringing the pad into the position shown in Figure 4, and allowing the device to be drawn out by means of hooked portions of the members 6 without fouling the fillet 4^x of the axle journal 4.

In order to allow free movement of the spring leaves 5 the pad 1 is made in two parts joined by strips 1^x of flexible material, the arrangement being such as to leave a space 14 which allows the journal 4 to be lubricated by oil splashing from the bottom of the axle-box 3, and although two longitudinal connecting members 8, 9 are shown between each pair of spring leaves 5 the lower of these may be dispensed with and the upper one 8 be provided with an extension to afford finger plates.

I claim:—

1. A supporting structure for a lubricating pad for a railway axle, said structure comprising a lower rectangular frame and an upper pad carrying frame and a resilient connection therebetween, said upper frame comprising an elongated member, the longitudinal axis of which is disposed substantially parallel to and at one side of a vertical axial plane of said axle, said lower rectangular frame comprising two elongated members disposed on opposite sides of said vertical axial plane, said resilient connection between said frames comprising a leaf spring fixed adjacent its ends respectively to said upper elongated member and one of said lower elongated members of said upper and lower frames, said leaf spring extending through said vertical axial plane and being adapted to urge said upper pad carrying frame into operative relation to said axle.

2. A supporting structure for a lubricating pad for a railway car axle in a journal box, said structure comprising a substantially rigid, rectangular lower frame, a plurality of upper pad carrying bars disposed on opposite sides of a vertical axial plane of said axle, and a resilient supporting connection between said bars and said frame, said connection comprising crossed spring members extending from said bars to said frame at opposite sides of said vertical axial plane, and means operable to depress said bars against the action of said resilient connection, whereby said supporting structure may be distorted in shape to facilitate its removal from said journal box.

3. A supporting structure for a lubricating pad for a railway car axle in a journal box, said structure comprising a substantially rigid rectangular lower frame, a plu-

rality of upper pad carrying bars disposed on opposite sides of a vertical axial plane of said axle, and a resilient connection between said bars and said frames, said connection comprising crossed spring members extending from said bars to said frame at opposite sides of said vertical axial plane, and means comprising finger piece extensions on said pad carrying bars and on said frame operable to depress said bars against the action of said spring members, whereby said supporting structure may be distorted in shape to facilitate its removal from said journal box.

4. A supporting structure for a lubricating pad for a railway axle in a journal box, said structure comprising a substantially rigid rectangular lower frame, upper pad carrying means, and a resilient connection therebetween, said lower frame comprising longitudinal side members and transverse end members fixedly connected together at the frame corners, said pad carrying means comprising a pair of bars, each disposed on opposite sides of a vertical axial plane of said axle, said resilient connection comprising oppositely extending crossed spring members disposed between each bar of said pair of bars and the longitudinal side member on the opposite side of said vertical axial plane, and means operable to flex said spring members to permit removal of said supporting structure from said journal box.

5. A supporting structure for a lubricating pad for a railway axle in a journal box, said structure comprising a rectangular lower frame, upper pad carrying means, and deformable connecting means therebetween, said lower frame member comprising longitudinal side members, transverse end members, and an upstanding bracket on one of said end members, said pad carrying means comprising a longitudinally extending bar disposed on each side of a vertical plane of said axle and a forwardly projecting extension on each of said bars, said deformable connection comprising oppositely extending crossed spring members disposed between said bars and said longitudinal side members on respectively opposite sides of said vertical axial plane of said axle, said deformable means also comprising a laterally extending arm rigidly secured to each said extension on said bars and fulcrumed at its opposite end on said upstanding bracket on said lower frame member, said extensions, arms, and brackets comprising means for flexing said spring members to permit removal of said structure from said journal box.

6. A supporting structure for a lubricating pad for a railway axle in a journal box, said structure comprising a substantially rigid rectangular lower frame, upper pad carrying means and deformable connecting

means therebetween, said lower frame having an upstanding bracket at one end thereof, said upper pad carrying means having forwardly projecting extensions disposed on 5 opposite sides of a vertical axial plane of said axle, said deformable connection comprising crossed spring members disposed between said rectangular lower frame and said pad carrying means and a laterally extending 10 tending arm rigidly secured to each of said forwardly projecting extensions and fulcrumed upon said upstanding bracket, said extensions, arms, and bracket comprising means for flexing said spring members to 15 permit removal of said structure from said journal box.
